UNITED STATES PATENT OFFICE

GEORGE H. BUTLER, OF LOS ANGELES, CALIFORNIA, ASSIGNOR TO NADIC, LTD., OF LOS ANGELES, CALIFORNIA, A CORPORATION OF CALIFORNIA

DESIGN FOR A CASING FOR COMBINED WEIGHING AND INSURANCE-VENDING MACHINES

Application filed August 14, 1929. Serial No. 32,410. Term of patent 14 years.

To all whom it may concern:

Be it known that I, GEORGE H. BUTLER, a citizen of the United States, residing at Los Angeles, in the county of Los Angeles and State of California, have invented a new, original, and ornamental Design for Casing for Combined Weighing and Insurance-Vending Machines, of which the following is a specification, reference being had to the ac-

companying drawing, forming part thereof.

The figure is a perspective view of the casing for combined weighing and insurance vending machines, showing my new design.

I claim:

The ornamental design for a casing for combined weighing and insurance vending machines, as shown.

GEORGE H. BUTLER.
